CONTROL SYSTEM

Paul S. Dickey, Shaker Heights, Ohio, assignor to
 Bailey Meter Company, a corporation of Delaware

Application July 24, 1940, Serial No. 347,191

6 Claims. (Cl. 122—504)

This invention relates to method and means for operating and controlling the operation of vapor generators; particularly vapor generators of the drumless, forced flow type, having a fluid flow path including one or more long small-bore tubes, in which the flow in the path is initiated by the entrance of liquid under pressure at one end, and the exit of vapor only at the other end; characterized by an inflow of liquid normally greater than the outflow of vapor, the difference being diverted from the path intermediate the ends thereof.

Such a vapor generator having small liquid storage and operated with wide range combustion devices forms a combination rendering practical extremely high heat release rates with the consequent ability to economically handle practically instantaneous load changes from minimum to maximum, and vice versa, without heavy standby expense, and is particularly suitable for operating conditions such as marine service, where load variations are of a wide range and are required to be met substantially instantaneously.

The generator has a minimum liquid storage capacity with a maximum heat absorbing surface so disposed and arranged as to be substantially instantaneously responsive to rapid changes and wide diversities in heat release rate in the furnace. The heat absorbing surface is arranged in relation to the path of the products of combustion and radiant heating so that the entering liquid is received at the cooler end of the path. Further, the vapor generator insofar as the passage of combustion gases is concerned has a continuously increasing resistance to gas flow throughout the length of the passageway.

The heat absorbing surface, or flow path for the working medium, is comprised of one or more long small-bore tubes with an enlargement, preferably at the end of the generating section, which acts as a separator to divide liquid and vapor. The vapor is then passed through a super-heater, while the excess liquid carried through the tubes for the purpose of wetness and preventing scale deposit, is diverted out of the separator under regulated conditions, as will be hereinafter set forth. From the separator there is a normal continuous and an additional regulated spillover or diversion of a part of the liquid entering the economizer under pressure, so that there is always being fed to and through the economizer and vapor generating sections more liquid than can be converted into vapor in a single passage therethrough, although the propor-

tion of such excess liquid may represent but a small part of the total volume of fluid passing through the vapor generator and is at most times only sufficient to insure tube wetness and to carry off scale forming materials.

In vapor generators of the character mentioned having small liquid and heat storage with high heat release capabilities, the liquid inflow must of necessity be continuous and at all times proportioned to the vapor outflow, at the same time taking into account the desired diversion of excess liquid from the flow path. Furthermore, to accomplish the wide range in heat release with substantially instantaneous response, and to perform the combustion process efficiently, a method and means for operating such a vapor generator in accordance with varying conditions must be provided.

Still another object is to provide a sequence and protective system for maximum safety of operation.

Further objects will become evident from a study of the specification and of the drawings, in which:

25 Fig. 1 diagrammatically illustrates a drumless forced flow vapor generator, combined with the requisite apparatus to control the functioning thereof, and shown in partially diagrammatic fashion.

30 Fig. 2 illustrates protective apparatus and circuits.

Fig. 3 shows a protective arrangement similar to Fig. 2.

In the various drawings, identical parts bear 35 the same reference numerals.

The drumless forced flow vapor generator of the type to which the present invention may preferably be applied is diagrammatically illustrated in Fig. 1.

40 The flow path for the working medium is comprised of a plurality of long small-bore tubes brought together at suitable headers. The generator includes an economizer 202 at the cooler end of the gas passage and which receives liquid from a pump 288.

These parallel flow circuits comprising the vapor generating surface tangentially enter a bulge in the fluid flow path, which is in the form of a separating chamber 232 for dividing the fluid into liquid and vapor; the vapor passing to a superheater 242, and the excess liquid being diverted from the fluid flow path through a pipe 1 to the hot well or to waste. This excess liquid may pass through heat exchangers, if desired. 45 A normal continuous spillover occurs through

the restriction 2, while a variable spillover occurs through the regulating valve 3.

The "heat source" includes an oil burner 4 supplied by a pipe 5 and an air chamber 6 supplied by a conduit 7. Initial ignition of the oil firing means is accomplished through the agency of an igniter means, which is disclosed and claimed in the copending application of Ervin G. Bailey and Paul S. Dickey, Serial No. 303,334, filed in the United States Patent Office November 7, 1939. The electrical control system and mechanism for actuating and controlling such ignition means is also disclosed and claimed in said copending application.

Referring now in particular to Fig. 1, I illustrate the fluid flow path as a single sinuous tube, to the economizer section 202 of which, liquid is supplied under pressure through a conduit 11 from a pump 289, which may be of any suitable type, and which I have therefore illustrated merely diagrammatically. From the economizer section the fluid passes to and through the generating section discharging into the separator 232. From the separator, vapor passes to and through the superheater 242, leaving by the conduit 244 to a main turbine 12 illustrative of a vapor consuming device. Products of combustion pass successively through the generating section comprising the furnace wall, superheater, and economizer and may contact a part or all of the separator.

An auxiliary turbine 287 drives the liquid feed pump 289, the air blower 288, and the fuel supply pump 290. While I have illustrated these devices diagrammatically and as though all are located to be driven by the same shaft and at the same speed, it will be understood that the necessary gear reduction, or driving connections between the several devices, are known and would be properly designed as to relative speed, power, etc., and that I merely intend to indicate that the auxiliary turbine 287 drives the devices 289, 288 and 290 simultaneously and in unison.

The rate of supply of fuel oil to the burner 4 is primarily controlled by the speed of the oil pump 290, but the supply of oil is further regulated by the throttling of a regulating valve 13 located in the pipe 5; and the rate of flow is continuously measured by a meter 14.

The rate of supply of air to support combustion is primarily determined by the speed of the blower 288, but is further under the control of a damper 15 positioned in the conduit 7, preferably at the inlet to the blower 288. The rate of supply of air is continually measured by a flow meter 16.

The rate of supply of liquid under pressure through the conduit 11 is primarily controlled by the speed of the pump 289, but is further influenced through the positioning of the regulating valve 17 at the suction side of the pump and by a regulating valve 18 in a by-pass around the pump.

In the operation of such a vapor generator certain variables are measured, indicated, and utilized as the basis for automatically controlling the supply of liquid thereto and the supply of the elements of combustion to the heating furnace.

I indicate at 19 a pressure responsive device, such as a Bourdon tube connected to the conduit 244 and having an indicator pointer 20 adapted to cooperate with an index 21 for advising the instantaneous value of the vapor out-

flow pressure. At 22 is indicated a temperature responsive device, such as a Bourdon tube, forming a part of a temperature sensitive system adjacent the conduit 244 and having an indicator pointer 23 adapted to cooperate with an index 24 for advising the instantaneous value of the vapor outflow temperature.

As an indicator of generator output, or load upon the vapor generator, I provide means actually measuring the vapor outflow through the pipe 244 leading to the turbine 12 or other utilizer. To this end I provide a flow meter 78, similar to the flow meter 14, and connected to the pipe 244 across an orifice or other restriction 79. The flow meter is adapted to vertically position a pilot stem 42 relative to a pilot casing 43 to vary an air loading pressure effective upon the relay 47 proportional to the rate of vapor outflow. The flow meter 78 furthermore positions a pointer relative to an index to continually advise the weight rate of vapor flowing through the conduit 244 as a guide to manual operation, and furthermore the meter 78 may, if desired, make a continuous record and/or integration of the weight rate of vapor outflow from the vapor generator.

29 represents means responsive to liquid level within the separator 232 and constitutes a pressure casing enclosing a mercury U-tube connected across the vertical elevation of the separator. A float is adapted to rise and fall with the surface of the mercury in one leg and to thus cause a positioning of a pointer 30 relative to an index 31 to advise the instantaneous value of liquid level within the separator.

The flow meter indicated in general at 14 for providing a measure of the rate of supply of fuel to the furnace is of a known type, such as is disclosed in the patent to Ledoux No. 1,064,748. Such a meter is a differential pressure responsive device adapted to correct for non-lineal relation between differential pressure and rate of flow, to the end that angular positioning of a pointer 32 relative to the index 33 is by increments directly proportional to increments of rate of flow. I illustrate by dotted lines within the flow meter 14 the outline of the internal construction wherein is a liquid sealed bell having walls of material thickness and shaped as described and claimed in the above mentioned Ledoux patent.

The flow meter 16 for measuring the rate of supply of air for combustion is similar to the meter 14 and positions a pointer 36 relative to an index 37 to provide a continuous indication of the instantaneous rate of flow of air supplied to the furnace.

I preferably primarily control the supply of liquid to the fluid flow path and the elements of combustion to the furnace, through variation in speed of the auxiliary turbine, utilizing the liquid inflow as the basis for such control. Realizing, however, the possible difference in characteristics of the pumps and blower, as well as variations in conditions of operation, I provide readjusting means to supplement the primary control of the elements of combustion. For the air, such readjusting means comprises the damper 15 positioned at the inlet to the blower 288 by a pneumatic actuator 38. For the fuel, the readjusting means comprises a regulating valve 13 positioned in the pipe 5 responsive to departure from desired relation of the measure of fuel flow and the measure of air flow.

The speed of the auxiliary turbine 287 is reg-

ulated through varying the opening of governor valves 39 adapted to admit relatively low pressure steam to the turbine, and at certain rates of operation to supplement this by additionally supplying relatively high pressure steam. For example, the low pressure steam may be the exhaust from the main turbine 12 or extraction steam therefrom, while the high pressure steam may be direct from the vapor generator. A pneumatic actuator 40 positions the valves 39 under the influence of an air loading pressure established by a standardizing relay 41. Such a standardizing relay is disclosed and claimed in the patent to Harvard H. Gorrie No. 2,098,914. In order to regulate the liquid inflow (through variation in speed of the water pump) I preferably accomplish the regulation responsive to liquid inflow rate, vapor outflow rate, and level of liquid in the separator.

As previously mentioned, the vapor outflow meter 18 is adapted to vertically position a pilot stem 42 relative to a pilot casing 43 to which a supply of compressed air may be available as indicated by the small arrow. Such a pilot valve forms the subject matter of a patent to Clarence Johnson No. 2,054,464, and in general is adapted to establish an air loading pressure directly representative of weight rate of vapor outflow passing the orifice 19.

I indicate pipes or tubes for transmitting such air loading pressures, throughout the drawings, by dotted lines to distinguish from electrical connections or other pipes or conduits. Such a connection is illustrated at 46 for transmitting an air loading pressure bearing a known relation to rate of vapor outflow to a differential relay device 47. Certain features of the differential relay 47 are disclosed and claimed in my Patent No. 2,098,913.

In similar manner the liquid level indicator 29 vertically positions a pilot stem 48 to establish at the relay 47, through the connection 49, an air loading pressure representative of liquid level.

The loading pressures transmitted through the pipes 46 and 49 are effective in separate chambers within the air relay 47 to establish an air loading pressure in the pipe 62 representative of the algebraic sum of said pressures. Such resultant air loading pressure is effective through the pipe 62 for positioning the valve 17.

The valve 17 acts as a variable or adjustable orifice across which there will exist a pressure differential bearing a known relation to the rate of fluid flow through the valve 17. Pressures on opposite sides of the valve are effective through the pipes 63, 64 respectively in separate chambers of the standardizing relay 41.

The standardizing relay 41 is to a certain extent similar to the relay 47 with the addition of a controllable bleed between chambers, which construction serves to allow an initial major correction with a tapering follow-up, and such regulation is effective through a pipe 68 to position the actuator 40. Certain features of the construction and operation of the standardizing relay 41 are disclosed and claimed in the patent to Harvard H. Gorrie No. 2,098,914.

In this instance the function of the controllable bleed connection of the standardizing relay is to supplement the primary control of the pressure effective upon the actuator 40 with a secondary control of the same or different magnitude as a follow-up or supplemental action to prevent overtravel or hunting, and wherein the positioning

of the actuator 40 will not necessarily be directly with the positioning of the valve 17.

In general, the valve 17 is positioned responsive to vapor outflow and to liquid level within the separator and forms a variable orifice in the suction line to the water pump. The device 41 receiving the differential pressure across the valve 17 positions the actuator 40 and the turbine valves 39 to control the speed of the water pump in such manner that the differential pressure across the valve 17 will be held constant regardless of the opening of the valve 17, and thus the liquid flow to the water pump is controlled proportional to vapor outflow and to liquid level within the separator.

If vapor outflow increases, then the pilot stem 42 is lowered proportionally, thus proportionally increasing the loading pressure effective through the connection 46, resulting in an increasing of the air loading pressure through the connection 62. The resulting change in opening of the valve 17 varies the pressure differential effective upon the relay 41, changing the loading pressure effective through the actuator 40 to position the turbine throttle valves 39, and results in an increased flow of water through the conduit 11 commensurate with the increase in vapor outflow from the vapor generator.

Should the liquid level within the separator 232 tend to fall, the pilot stem 48 will be raised, thus increasing the loading pressure in the proper chamber of the relay 47, and in like manner further opening the valve 17 to result in an increase in the supply of liquid to the vapor generator.

It will then be observed that the valve 17 is positioned responsive to vapor outflow from the generator and to liquid level in the separator, while the speed of the water pump is not only responsive to these two variables but additionally to the rate of flow of water to and through the pump.

The liquid level responsive device 29 further controls, through the pilot stem 48, the positioning of the variable spillover valve 3 in such manner that upon a rise in liquid level within the separator 232 above a predetermined elevation there will be a regulated opening of the valve 3 to supplement the normal continuous spillover 2 to the pipe 1.

Certain features directed to the control of the auxiliary turbine are disclosed and claimed in my Patents 2,163,592 and 2,170,348. Certain features relating to multiple and sequential control from liquid level within the separator are disclosed and claimed in the patent to Ervin G. Bailey and Paul S. Dickey, No. 2,211,725.

Under the control of vapor outflow pressure acting upon the Bourdon tube 19, I provide a pilot valve 69 for establishing an air loading pressure through the connection 70 to position the bypass valve 18 and the damper 15. Upon a fall in vapor pressure from predetermined value the valve 18 and the damper 15 both tend to open, each from a predetermined position. This action is particularly desirable upon sudden material increase in load upon the unit as a whole, thus causing a marked decrease in vapor pressure. When such sudden and material increases in vapor outflow occur, thereby lowering the vapor pressure, the auxiliary turbine speed is increased and the damper 15 is opened. At such time it is desired to increase the supply of fuel and air without an immediate increase in the supply of liquid. By-passing the pump 289 by means of the valve 18 reduces liquid flow through conduit 11

and valve 17 and causes the auxiliary turbine 287 to speed up to restore the original liquid flow, and in so speeding up increases the air flow and fuel flow rates. Without the by-pass 18, not only would this advantage be lost, but the momentary increase in liquid inflow when the auxiliary turbine speed is increased, would be more than would be desired to utilize the available heat storage of the unit. The adjustment of the actuator 38 and of the actuator of the valve 18 is preferably such that they will be responsive only to predetermined variations in vapor pressure and corresponding air loading pressure in the connection 70. For example, the damper 15 may be regulated as to position upon any departure of vapor pressure from predetermined value in either direction, while the valve 18 may be completely closed until vapor pressure has fallen a predetermined amount below the desired standard. Beyond that point the valve 18 would begin to open and the damper 15 may, or may not, be completely open while the opening of the valve 18 is being regulated.

I preferably primarily control the supply of the elements of combustion through varying the speed of the auxiliary turbine, and thereby the speed of the blower and the oil pump in unison with the liquid inflow rate. Having readjusted the air supply through a positioning of the damper 15, and provided a measure of the air flow by the meter 16, I then utilize the regulating valve 13 in the oil supply line to properly proportion fuel to air. To this end the meters 14, 16 are interconnected with linkage 71 for positioning a pilot stem 72 to establish an air loading pressure through the connection 73 to a standardizing relay 74 in general construction similar to that illustrated at 41. The air loading pressure resultant from operation of the relay 74 is effective through a connection 75 for positioning the regulating valve 13 upon departure of air flow-fuel flow relation from predetermined value.

A method and apparatus of electrical protection of such a power system is disclosed and claimed in my Patent No. 2,170,346, as well as being disclosed and claimed in part in the co-pending application of Jack F. Shannon, Serial No. 55,028, filed December 18, 1935.

Figs. 2 and 3 in general show the protective arrangement and circuit for the vapor generator, in which a series electric circuit is arranged to normally hold open the solenoid valve supplying control air to the fuel shutoff valve 108 and to pilot valve 69. Upon loss of electrical power at the solenoid valve the valve closes, shutting off the air pressure from the fuel supply valve and thus cutting off fuel supply to the furnace. The normally energized solenoid of the valve is in a series circuit including normally closed contacts which are arranged to open the solenoid circuit upon excessively high pressure at the separator drum, low water in the separator drum, low pump lubricating oil pressure, flame failure, or from excessively high temperature experienced in any of the individual furnace circuits. Thus any one of the mentioned emergency conditions will be effective in tripping the fire through shutting off the fuel supply valve 108 to the furnace.

In addition to the protective circuits mentioned I have illustrated in Figs. 2 and 3 preferred arrangements of emergency operation of the spillover valve 3 under certain steam pressure conditions.

In the operation of a forced flow vapor generator of the type herein disclosed, locomotive service and marine service in particular demand

extreme magnitude and rapidity of load changes. It is, for example, not uncommon to have such a vapor generator operating at an overload and almost instantaneously drop the load to say 1%.

5 This sudden substantially complete loss of load may cause the steam pressure to rise very rapidly. The high pressure trip of Figs. 2 and 3 will shut off the fire, but the stored heat in the furnace causes the pressure to go on up in spite of 10 that and to blow the safety valve. It is, of course, not desirable to frequently blow the safety valve on a vapor generator operating at pressures in the order of twelve hundred pounds and greater. Upon a sudden loss of load and increase in 15 pressure the entire water storage of the vapor generator shrinks. The continuance of incoming water fills the unit as high as the normal level control of the separator drum will allow it to fill, and the relatively cool incoming water 20 causes the stored water to shrink further. Then when the load returns suddenly and to great extent all of the water immediately swells, filling the drum and possibly carrying over into the superheater and/or the turbine. This may happen before the normal drum level control can 25 drain the separator drum down to a safe operating level.

Both of these conditions indicate the desirability of opening the spillover valve 3 widely 30 under emergency high pressure conditions. The arrangements of Figs. 2 and 3 preferably dump the separator drum by opening the spillover valve immediately and completely when an excessive vapor pressure is experienced.

35 Such an opening of the spillover valve relieves the pressure (thus saving the safety valves from blowing) and may blow the separator empty, discharging hot water and saturated steam to the hot well. This does no harm however as the 40 heat exchangers or hot well will utilize the heat of the water and steam. In the meantime the incoming water from the feed pump continues and cools the circuit. Furthermore, by blowing the separator drum through the spillover valve 45 immediately after a loss of load, and having a minimum water storage in the unit, minimizes the danger of carry-over due to swell upon a recurrence of load.

50 My arrangement thus provides that if an excessively high steam pressure is experienced, either from sudden loss of load or for other cause, the fire will be tripped off through a closing of the fuel supply valve 108 and the spillover valve 3 will be opened widely to blow down the separator drum. It is preferable that 55 as the pressure increases it first causes a tripping of the fire and immediately thereafter (or at a slightly higher pressure value) causes an opening of the spillover valve. This is so that the separator will not be empty with the fire 60 lighted and to avoid the danger of burning the separator. It is therefore essential always to trip the fire before blowing down the separator drum.

65 In Fig. 2, in addition to the protective circuits previously described, the air loading pressure developed by the pilot 69 is led to one chamber of a standardizing relay 109 from which a control loading pressure leads to a differential relay 110. The latter also receives a second loading pressure developed by the level controller pilot 49, which loading pressure in Fig. 1 goes directly to the spillover valve 3. In Fig. 2 the spillover valve 3 is controlled by the loading pressure from the 70 relay 110, resultant between that established by 75

the pilot 69 and that established by the pilot 49.

The construction and biasing of the relay 110 is such that the emergency loading pressure from the pilot 69 is normally ineffective upon the relay 110 until a certain predetermined high steam pressure is obtained, whereafter this loading pressure comes into effect on the averaging relay 110 and overbalances the loading pressure representative of drum level, thus taking the control of the valve 3 away from the level controller and causing the valve to open widely and promptly.

In Fig. 3 the arrangement differs somewhat from that of Fig. 2 in that while the averaging relay 110 is normally under control of a loading pressure from the level control pilot 49 for positioning of the spillover valve 3, there occurs under an emergency condition an opening of a solenoid valve 111 in an air supply line to a second chamber of the relay 110 to immediately open the spillover valve wide. In this arrangement the solenoid valve 111 will be actuated in parallel with the solenoid valve which causes the shutting off of the fuel supply valve 108 and from any one of the emergency trips previously described.

It will be appreciated that there may be many modifications and arrangements possible of the illustrative example given herein, without departing from the spirit of my invention, and that I have illustrated and described only preferred embodiments without intending them to be limiting.

What I claim as new, and desire to secure by Letters Patent of the United States, is:

1. The method of operating a vapor generator of the forced flow type receiving liquid under pressure at one end of the flow path and delivering superheated vapor at the other end, which includes, supplying liquid in predetermined excess over vapor outflow, discharging the liquid-vapor mixture to a separator between the generating and superheating portions of the path, utilizing the liquid level in the separator to so control the discharge therefrom as to maintain a predetermined level therein under normal load conditions and increasing the rate of blowing down of the separator when a predetermined low load condition on the generator and a corresponding low firing rate of the generator is experienced.

2. The method of operating a vapor generator of the forced flow type receiving liquid under pressure at one end of the flow path and delivering superheated vapor at the other end, which includes, supplying liquid in predetermined excess over vapor outflow, discharging the liquid-vapor mixture to a separator between the generating and superheating portions of the path, utilizing the liquid level in the separator to so control the discharge therefrom as to maintain a predetermined level therein under normal load conditions and increasing the rate of blowing

down of the separator when a predetermined high pressure in the generator is experienced following a low firing rate of the generator.

3. The method of operating a vapor generator of the forced flow type receiving liquid under pressure at one end of the flow path and delivering superheated vapor at the other end, which includes, supplying liquid in predetermined excess over vapor outflow, discharging the liquid-vapor mixture to a separator between the generating and superheating portions of the path, utilizing the liquid level in the separator to so control the discharge therefrom as to maintain a predetermined level therein under normal load conditions and increasing the rate of blowing down of the separator when there is no load on the generator and the firing rate of the generator ceases.

4. The combination of a vapor generator of the forced flow type, means supplying liquid under pressure to one end of the forced flow path in excess over vapor generated, a liquid-vapor separator in the flow path between the generating and superheating portions of the path, a meter continuously determining liquid level in said separator, a valve controlled by said meter and variably discharging liquid from the separator, and means responsive to a predetermined low load condition and corresponding low firing rate of the generator adapted to increase the rate of blowing down of the separator through additional opening of said valve.

5. The combination of a vapor generator of the forced flow type, means supplying liquid under pressure to one end of the forced flow path in excess over vapor generated, a liquid-vapor separator in the flow path between the generating and superheating portions of the path, a meter continuously determining liquid level in said separator, a valve controlled by said meter and variably discharging liquid from the separator, and means responsive to a predetermined high pressure condition in the generator following a low firing rate of the generator adapted to increase the rate of blowing down of the separator through additional opening of said valve.

6. The combination of a vapor generator of the forced flow type, means supplying liquid under pressure to one end of the forced flow path in excess over vapor generated, a liquid-vapor separator in the flow path between the generating and superheating portions of the path, a meter continuously determining liquid level in said separator, a valve controlled by said meter and variably discharging liquid from the separator, and means responsive to the shutting off of the fire following loss of load on the generator adapted to increase the rate of blowing down of the separator through additional opening of said valve.

PAUL S. DICKEY.
